UNITED STATES PATENT OFFICE.

EDWARD P. McDONALD, OF PITTSFIELD, MASSACHUSETTS.

DEVICE FOR FITTING HATS.

SPECIFICATION forming part of Letters Patent No. 424,336, dated March 25, 1890.

Application filed December 19, 1889. Serial No. 334,287. (No model.)

To all whom it may concern:

Be it known that I, EDWARD P. McDONALD, a citizen of the United States of America, residing at Pittsfield, in the county of Berkshire and State of Massachusetts, have invented certain new and useful Improvements in Devices for Fitting Hats; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 My invention relates to certain new and useful improvements in attachments for hats, the object thereof being to provide a means whereby the inner diameter of the hat may be decreased; and it consists of two curved wires 20 of different diameters secured to each other and adapted to be applied between the sweat-band of the hat and the body thereof.

In the accompanying drawings, Figure 1 is a sectional view of a hat, showing my invention applied thereto; and Fig. 2 is a perspective view of my improved device for hats.

25 A refers to the body of the hat, and B the sweat-band, which is secured to the body in the usual manner. Between the body of the hat adjacent to the rim thereof and beneath the sweat-band my improvement is adapted to be applied, and said improvement consists of two wires C and D of different diameters, which are bent to 30 conform to the internal configuration of the hat, the ends thereof being secured to each other by loops E, which may consist of sheet metal bent in circular form and provided with extended ends within which the wires C and 35 D lie, so as to be held either by welding or

soldering. These wires are also held together at their central or intermediate portions by clasps F, which may be merely a strip of metal bent at each end to encircle said wires. The wires may be of different lengths, so that one 45 will flare outwardly more than the other, thus giving a greater range to the device.

It is well known in practice that hats after being worn a little stretch or become enlarged, and then the device is especially serviceable, and may be applied to a hat, the smaller wire D being placed adjacent to the rim of the hat beneath the sweat-band, thus making the hat slightly smaller. If the hat is stretched excessively the larger wire may 55 be placed downwardly, thus making the hat still smaller.

This device when applied to felt hats or those of soft material will hold them in shape, and it can be applied to new hats as well as 60 old ones.

I claim—

1. A device for hats, consisting of a metallic band made up of two wires of different diameters, the ends of which are secured to 65 each other, substantially as and for the purpose set forth.

2. In combination with the curved wires C and D of different diameters arranged one above the other, the ends thereof being connected to each other, of loops for securing the intermediate parts, the same being designed to be placed beneath the sweat-band of a hat. 70

In testimony whereof I affix my signature in presence of two witnesses.

EDWARD P. McDONALD.
